Application March 17, 1948, Serial No. 15,358

9 Claims. (Cl. 216—54)

1

The present invention relates to apparatus for applying labels to containers and particularly to containers of the bottle and can type.

One of the objects of the invention is to provide a labeling apparatus capable of extremely high speed operation which will automatically, initially, apply to the back of a label a suitable adhesive and then apply the label to the container, afterwards ironing the label on the container to smooth out any wrinkles which may have occurred in the label during the application thereof, and causing the label to adhere closely to the container with sufficient adhesive to secure the label in position and to quickly dry after application.

Another object of the invention is that of providing, in a labeling machine, means for automatically dating or applying other indicia to the label for identification purposes. Preferably the invention relates to means for applying the identification indicia to the back of the label immediately prior to the application of the label to the container.

Another object of the invention is to provide an improved means for receiving the labels singly from a magazine and positioning the same to be applied to the container.

Another object of the invention is to provide an improved means for ironing the label on the container after the container has received the label from the positioning means.

Further objects and advantages of the invention will appear more fully hereafter in the appended specification and claims.

For the purpose of disclosing the invention certain embodiments have been illustrated in the accompanying drawings in which:

Fig. 1 is a partial plan view, partially diagrammatic, of the rotating container supporting table and associated parts;

Fig. 2 is a longitudinal sectional view showing the drive mechanism, the container supporting table, and the operating means for the container grippers;

Fig. 3 is a side elevation of that portion of the machine embodying the glue applying means and the dating means;

Fig. 4 is a side elevation, looking in the direction opposite of that in Fig. 3, showing the means for operating the label pickers and associated parts;

Fig. 5 is a partial front elevation of the label picker means and associated parts;

Fig. 6 is a diagrammatic view showing the

2

travel of the container and the position of the label ironers;

Fig. 7 is a detail plan of the label ironers shown in Fig. 6;

Fig. 8 is a detail section on the line 8—8 of Fig. 3;

Fig. 9 is a sectional view taken on the line 9—9 of Fig. 5;

Fig. 10 is a side elevation of a magazine label holding finger;

Fig. 11 is a side elevation of the modification of the neck label holding finger, illustrated in Fig. 10;

Fig. 12 is a side elevation showing more in detail the dating mechanism;

Fig. 13 is a side elevation showing the glue applying roller and the dating roller;

Fig. 14 is a detail view showing the means for normally biasing the picker fingers toward one another;

Fig. 15 is a front elevation of a modified form of picker fingers and the support therefor;

Fig. 16 is a side elevation of the structure illustrated in Fig. 15;

Fig. 17 is a plan view of a modified form of a holding finger for the infeed star together with the bottle aligning block;

Fig. 18 is a front elevation thereof; and

Fig. 19 is a plan view of a modified form of holding finger for the out-feed star.

For the purpose of description, the containers to which the labels are to be applied will be referred to as bottles, although it is understood the apparatus is adapted to apply labels to other types of containers.

In the apparatus illustrated we provide a rotary table or support, carrying a plurality of container supporting platforms 1. Each of these platforms is adapted to receive a bottle which is gripped at its top by a top gripper 2 carried on a gripper arm 3, supported on a gripper support rod 4 (Fig. 2). As the bottle receiving table and platforms 1 rotate in a clockwise direction each table receives a bottle from an infeed star 5.

This star is provided with a plurality of pairs of gripper fingers. One of the pairs 6 is relatively stationary, on the star, and the other finger 7 is adapted to move relatively to the first mentioned finger position after the finger 6 has engaged and removed from the conveyor a bottle.

With the bottle gripped between the fingers 6 and 7 the bottle is moved across a table 8 and wholly positioned on a supporting platform 1 beneath the top gripper 2 which, after the bottle has been positioned, descends and engages

the top of the bottle, maintaining the same substantially rigid on the supporting platform.

The supporting rod 4 (Fig. 2) is raised to non-gripping and lowered to gripping position through the medium of a cam 9 on which rides a roller 6, carried in an arm 11, pivoted on the supporting platform 1 and biased in a downward direction by a coiled spring 12. The free end of this arm 11 is connected by a link 13 with a collar 14 on the rod 4. Accordingly as the platforms 1 rotate each of the grip operating rods 4 will be raised to open position to permit the gripper to receive a bottle and after receiving the bottle will be moved downwardly, under the influence of the coiled spring 12, to grip the bottle and maintain the same in position.

After the bottle has been gripped on its supporting platform 1 it moves to a position to receive a label carried on the picker fingers 15. These picker fingers may be in pairs, as illustrated in Fig. 5, one pair for the body label and the other pair for the neck label. The picker fingers 15 are disposed in spaced relation on a pair of carrying arms 16. These arms 16 are pivotally mounted on a support 17 so that they may move toward and away from one another and are biased toward one another by a coiled spring 18 interposed between a pair of lugs 19, one on each arm. Adjustable stops 20 are provided for limiting the throw of the arms. The picker fingers 15 may be of plastic material having their inner edges inclined to provide cam surfaces. These cams are engaged by the bottles to spread the arms as the bottles pass therebetween.

The support 17 is reciprocably mounted on a shaft 21 which is supported in a head 22 at the top of the frame 23. The arms are oscillatingly supported on the shaft 21. For reciprocating the support 17 on the shaft 21, to initially position the picker fingers beneath the label magazine, we provide an oscillating arm 24 pivoted at its lower end at 25 to an extension of the frame 23 which extension projects through an opening in the base 26 of the machine. This arm is provided with a roller 27 operating in a cam slot 28 on a rotating cam 29. This cam 29 is rotated through a suitable bevel gear drive 30 from the driving mechanism of the machine.

The magazine 31 for the labels is supported to one side of the path of travel of the platform 1 and supports the labels in stacked relation. To remove the labels, one at a time, from the magazine the picker fingers move transversely on the shaft 21 to a position in front of the magazine (Fig. 4) and are then oscillated on the shaft to engage with the picker fingers of the stack. The bottom label having previously been covered with a film of adhesive, the label will stick to the picker fingers and be removed therewith as the picker fingers oscillate to their initial position. After having been oscillated to their initial position they are then moved transversely on the shaft 21 to a position in the path of travel of the bottles.

The oscillating movement of the picker support 17 is accomplished by an oscillating rod 32 which has sliding engagement in a groove in the support 17 such as is illustrated at 17' in Fig. 16. This rod is supported at its opposite ends in arms 33 rotatably mounted on the shaft 21 and the oscillating movement is imparted to these arms through the medium of reciprocating rod 34 connected to one of the arms 33 by a link 35. Reciprocating movement is imparted to the rod 75 of the roller 67 and the inking roller 54 is such

34 by a cam roller 36 operating in a cam slot 37 formed in a cam wheel 38. The roller 36 is carried on the free end of an arm 39 pivoted at 40 to a frame 23 and is connected to a collar 41 surrounding the lower end of the rod 34. This collar slidably operates on the rod 34 but moves the rod upwardly through a medium of coiled spring 42 interposed between the collar 41 and a fixed collar 43 on the rod. Mention should be made of the fact the rod 34 is formed in two sections held together by a threaded joint member 44 to permit vertical adjustment of the rod.

There are occasions when the star wheel 5 fails to deliver a bottle to one of the supporting platforms 1. Also there are occasions when through accident a bottle is broken. Under these circumstances it would be undesirable for the picker fingers to continue to oscillate to receive a label from the magazine. This would result in the piling up of the labels on the picker fingers. To avoid this contingency, the gripper rod 4, unless a bottle is located beneath the same, will move downwardly until the enlarged portion 45 is in the path of the trip lever 46. The trip lever will be rocked on its pivot, in turn rocking a lever 47 (Fig. 8) which engages a rod 48 projecting the free end 49 of this rod into the path of and above, an arm 50 on the lower end of the rod 34. Accordingly rod 34 will be locked in its lower-most position and although the collar 41 moves upwardly under the operation of the cam wheel 38 the spring 42 will be compressed without in any way affecting a movement of the rod 34.

35 The adhesive or glue is applied to the surface of the picker fingers, to be eventually transferred from the picker fingers to the rear face of the label, through the medium of a glue applying roller 51 which is adapted to roll across the face of the picker fingers when they are in their retracted position. This roller 51 receives the glue from a feeder roll 52 dipping into a glue pot 53. A dater roller 54 moves with the glue applying roller for the purpose of applying a date or other indicia to the back of the label immediately prior to its being placed upon the bottle. This glue applying roller 51 is supported on a shaft 55 carried in a guide head 56 which travels between a pair of guide members 57 and 58 suitably supported on a bracket carried on the frame 23. The guide head 56 is reciprocated to move the glue roller 51 across the faces of the picker fingers by operating rod 59 connected at its lower end to the free end of a lever 60 pivoted at 61 to the supporting frame. This lever carries a cam roller 62 operating in a cam slot 63 in a cam wheel 64 driven from the driving mechanism of the apparatus. The dating roller 54 is carried on a bracket 65 (Figs. 12 and 13) which is secured upon an arm 66 swingably mounted on the shaft 55. This arm, at its lower end, carries roller 67 which operates between a pair of tracks 68-68 formed on the inner face of track plate 69. The plate 69 is pivotally mounted at 70 on guide rail 58 and is substantially L shaped, the track slot between the tracks 68 having substantially the same conformation. The short leg of the L plate is biased upwardly by coiled spring 71 interposed between a lug on the plate and a lug on a finger 72 secured to the track 58 and spaced apart from the bottom edge of the plate 69. An inking pad 73, facing downwardly, is secured beneath the label magazine 31 and the arrangement of the travel path 70 of the roller 67 and the inking roller 54 is such

that as the rollers drive downwardly with the glue roller this guide roller 67 will move between the tracks 68. In the horizontal portion of the tracks the dater roller is forced against the bottom face of the inking pad 73. As the roller 67 passes out of the track it moves downwardly beneath the bottom edge of the plate 69 and the finger 72. As the glue roller moves upwardly the roller 67 will move rearwardly, carrying with it the dating roller 54, and then upwardly, on the rear edge of the plate 69. During the upward movement of the roller 67 this roller will ride along the back edge of the plate 69 and out of contact with the labels supported in the label holder. After the roller 67 commences to descend it moves between the tracks 68 and by these tracks is guided in such a manner as to cause the printing roller 54 to ride across the rear face of the first label of the label stack.

During this reciprocating movement the glue roller 54 will ride across the face of the picker fingers 15 applying a film of glue to these picker fingers. It is to be noted that due to the shape of the cam 64, the picker fingers will be swung forward, part way, for a period long enough for the glue roller to ride across the faces of the picker fingers and by the time the glue roller has moved down to its bottommost limit of its stroke, the continued movement of the picker fingers will move them into engagement with the first label of the stack to thereby pick the label from the stack.

It should be mentioned that the application of the date to the rear face of the label is not affected by the application of glue thereto, and this is particularly so where, as is frequently the case, the glue is applied to the edges of the label only. While in the drawing, we illustrate a glue roller sufficiently wide to cover the faces of the picker fingers 15 it is obvious that a modified roller could be used which would apply glue only to the outer edges of the picker fingers.

Immediately after the label is taken by the picker fingers from the magazine, the picker fingers are moved transversely on the shaft 21 into the path of travel of the bottle. Accordingly as the bottle moves it passes between the picker fingers 15 picking up the label in its passage. The label is held on the bottle by adhesive on the back of the label, but to insure the retaining of the label in position until the label moves to the ironers, a holder finger 74 mounted on an arm 75 is moved into engagement with the label through the instrumentality of a lever arm 76 cooperating with a cam 77 and biased into engagement by the spring 78.

As the bottle continues in its rotary path it passes between a pair of ironers 79, 79 (Figs. 6 and 7) disposed on opposite sides of the path of travel and between which the bottle passes to the discharge end of the labeler. Each of these ironers comprises a flat plate 80 mounted on studs 81 extending through a mounting plate 82 and having bolt heads 83 on the ends thereof. This plate 80 is biased toward the path of travel of the bottle by coiled springs 84 surrounding the studs 81. Over the face of the plate 80 is secured a flexible ironer 85 which is secured at its ends to the downturned ends 85 of the plate 80. The ironer 85 may be formed of leather or other suitable material and is of sufficient length so that when the two ends are secured to the plate 80 the ironers will be bowed outwardly to form resilient pressure members adapted to

bear on the bottle as it passes between the ironers. As a result as the bottle passes between the ironers the label on the body of the bottle is pressed into intimate contact with the bottle and any wrinkles which may occur are thoroughly smoothed out.

The structure of the holder finger 75 is more fully illustrated in Figs. 10 and 11, Fig. 10 showing one form of presser arm and Fig. 11 showing another form. The structure illustrated in Fig. 10 is not only constructed to engage a body label but also to engage a top neck label or foil while the structure illustrated in Fig. 11 is adapted to engage a body label, a top neck label, and an intermediate neck label. Referring to the structure illustrated in Fig. 10 the presser arm 74 comprises an upright 87 which is vertically, adjustably secured to the arm 75 and has at its upper end an inwardly projecting neck 88. This neck is provided on its tip with a preferably soft rubber pad 89, which when the arm 75 is moved into engaging position, will bear upon a label or foil which is positioned at the top of the neck of the bottle. On the vertical portion of the upright 87 there is provided a bearing pad 90 which is secured in a block 91 held on the upright 87 by bolts 92 surrounded by coiled springs which bias the pad block 91 outwardly while permitting the block to move relatively to the upright 87 to accommodate different sized or different shaped bottles.

In the structure illustrated in Fig. 11 in addition to the neck label pad 89 and the body label pad 90, there is provided a supplemental pad 93 seated in a pad holder 94 on the inclined portion 88. This pad holder like the pad holder 91 is secured in position by bolts 95 surrounded by coiled springs which bias the pad holder outwardly away from the inclined portion 88 and towards the bottle. This pad is arranged to engage a label which might be applied to the neck of the bottle between the body label and the top neck label or foil.

After the bottle with its attached label has passed between the ironers it is picked up by the cut-feed star 96 and delivered to the conveyor for transfer away from the machine. This star is provided with a plurality of pairs of fingers. One finger of each pair is curved and faced with a pad of sponge rubber 97 and the other finger 98 of the pair is movable to open to receive the bottle and then closed to grip the bottle during its transfer from the supporting table to the conveyor. The gripper arms on the star are curved to conform to the face of the bottle with the sponge rubber pad 97 being on that arm which engages that portion of the bottle having the label. This pad will further tend to force the label into intimate contact with the bottle.

In applying the label to the bottle it sometimes happens that the glue squeezes out from beneath the label and as a result it is not unusual for the front face of the label to receive a certain amount of the glue. This glue during the movement of the bottle through the machine is apt to become tacky and as a result the label might stick to the pad 97. To avoid this contingency the pad is provided with one or more perforations 99 extending through the pad from the rear face. These perforations are connected by a feeder pipe 100 with a tank 101 mounted on the top of the shaft of the cut-feed star 96 so that a constant drip of water from the tank 101 may be fed to the front face of the pad, moistening the same and preventing any glue which may be on the front face of the label from becoming so

tacky as to cause the label to adhere to the pad. The drip of the water may be controlled by suitable valve 102, one for each of the pipes 100.

In Figs. 15 and 16 we have illustrated a modified construction of the support for the picker finger arms 16 and a modification of the picker fingers themselves. As has been heretofore explained as the bottles pass between the picker finger arms these picker finger arms are adapted to spread laterally to accommodate the passage of the bottle. In some instances it has been found desirable to provide for a swinging movement of the picker finger arms in the direction of travel of the bottles.

As illustrated in Figs. 15 and 16 the support 17 which reciprocates on the shaft 21 is provided with a pair of downwardly extending ears 103 through which extend pivot pins 104 having heads 105. As the picker finger arm supports are the same a description of one will be sufficient. The head 105 has bolted thereto a bracket 106 provided with rearwardly extending ears 107 and bolted to the head 105 by a securing bolt 108. To prevent relative rotation between the head 105 and the bracket the bracket is provided with a lug 109, on its face, which coincides with a slot on the rear face of the head 105. A supporting bracket 110 is swung on a shaft or pin 111 supported in the ears 107. This supporting bracket, in side elevation, is substantially L-shaped and is provided with a downwardly extending leg 112 to which is bolted the picker finger arms 113. The inner face of this leg 112 is provided with a recess to receive a cooperating lug 114 on the picker finger arm, the picker finger arm being secured in position by a suitable bolt 115. To bias the picker finger arm to normal position a bolt 116 is secured in the head 106 and extends through an opening in the bracket 110, a coiled spring 117 is interposed between the bracket and the head of the bolt.

To bias the picker finger arms toward one another each of the heads 105 has secured thereon an arm 118 which extends upwardly and between the two arms 118 is interposed a coiled spring 119 setting over suitable pegs 120 on the inner faces of the arms 118. To secure proper spacing of the picker finger arms adjustable stops 121 are provided for the arms 118.

By the above arrangement it is apparent that the picker finger arms may move laterally, relatively to one another, on the pivot pins 104. At the same time the picker finger arms may swing longitudinally of the path of travel of the bottle on the pivot pins 111. In each instance however, the finger arms are biased in their normal position through the means of suitable springs.

The picker finger arms when they are positioned above the travelling platform and in a position to permit the passage therethrough of a bottle, to pick up its label, would normally extend at an angle to the vertical axis of the bottle and therefore, would be out of parallelism with the sides of the body of the bottle. As a result, as the bottles approach a label, they would strike the top edge of the label first and, due to the high speed of travel, there would be a tendency to either distort the label or tear the same. Accordingly in the structure illustrated in Figs. 15 and 16 the lower end 122 of each of the picker finger arms is bent at an angle with respect to the body of the finger arm, this angle being such as to lie parallel with the axis of the bottle thus maintaining the label in parallel relation with the body of the bottle so that the whole surface,

from top to bottom, of the label will be engaged at the same instant.

In certain types of bottles, particularly in that type of bottle having an octagonal body portion, it is extremely important that the bottle be presented to the picker finger arms in an exact position. Therefore, it is important that the bottle be placed on the table supports 1 in an exact position. Accordingly we have illustrated in Figs. 17 and 18 a receiving gripper corresponding to the gripper 6 illustrated heretofore, so arranged that the bottle will be properly positioned. In these figures the gripper 6 is provided on its gripping face with upper and lower flat projections 123, 124, the flat surface of the projection 123 being so disposed that when the bottle is properly positioned one of the flat surfaces of the bottle will rest against the flat surface of the projection 123. Cooperating with the finger 6 of the type illustrated in Fig. 17 is a positioning pad or block 130 which is secured on the top face of each of the tables or platforms 1 by suitable bolts 131. This pad is provided with an opening 132 to accommodate the gripper support rod 4 and is provided with a plurality of flat faces 133, 134 and 135, so disposed as to form a pocket having one elongated side 136 into which the bottle is moved by the transfer finger 6 and its associated gripping finger 8 on the infeed star 5. As a result of this arrangement, bearing in mind that the table 1 and the infeed star are rotating tangentially, by the time the gripper finger 6, with the bottle pressed against the flat surface 123 by the movable finger 7, has reached a position to deposit a bottle in the positioning pad 130 the movable finger 7 will have moved out of engagement with the bottle and the spring fingers or plungers 125, biased in a projected position by the coiled springs 126, will force the bottle into the pocket formed by the faces 133, 134 and 135 and the bottle will be properly positioned to receive a label as it passes between the picker fingers.

It is to be understood of course that the positioning pad or block 133 is comparatively flat and extends no great distance above the top of the table 1.

In Fig. 1 and the associated figures we have illustrated the presser pad 97 as arcuate in shape and in most instances this presser pad has been extremely satisfactory. In some instances however, particularly with the octagonal body shaped bottle, we have found it more advantageous to provide means for exerting pressure on the flat surfaces of the bottle. Accordingly in Fig. 19, we have illustrated a modification of the pad 97 which consists of a plurality of sponge rubber, or other satisfactory material, blocks 127, 128 and 129 which are maintained in an angle relation to one another by a bracket 136 secured on the supporting finger 137. Accordingly when the bottle is deposited in position and pressed by the movable finger 98 against these pads, the label will be pressed and ironed smoothly in position. It is obvious that, if desired, the front faces of these pads could be moistened in the same manner as are the pads 97.

We claim as our invention:

1. In a labeling machine, in combination, a rotary table, a container support mounted upon said table, a label picker disposed adjacent to path of travel of said support and movable into and out of the path of said container support and comprising a supporting member, a pair of spaced apart picker finger arms pivotally

mounted at their upper ends on said supporting member, on axes extending in the direction of the path of travel of the container support to permit the lateral separation of said arms by the engagement of a container therewith to accommodate the passage of the container therebetween and on axes extending longitudinally of said path, a pair of ears secured to said picker finger arms and extending above the pivot point of said arms, a spring interposed between said ears to urge the lower end of said arms toward one another and spring means effective to permit limited longitudinal movement of said arms.

2. In a labeling machine, in combination, a rotary table, a container support mounted upon said table, a label picker disposed adjacent said table, and comprising an oscillating supporting member, a pair of spaced apart picker finger arms pivotally mounted at their upper ends on said supporting member on horizontal axes extending transversely of the path of said supporting member to permit said arms to swing in the direction of the path of travel of said supporting member, means for limiting the movement of said arms in the opposite direction and means for urging said arms toward said limiting means.

3. In a labeling machine, in combination, a rotary table, a container support mounted thereon, a label picker disposed adjacent said table, and movable into and out of the path of said container support and comprising a supporting member, a pair of spaced apart picker arms pivotally mounted at their upper ends on axes disposed in the direction of the path of travel of the container support to permit said arms to separate to accommodate the passage therebetween of a container, means for urging said arms toward one another, horizontally disposed pivots for said arms extending transversely of the path of the container support to permit said arms to swing in the direction of the path of travel of said container support, and means for urging said arms in a direction opposite to the direction of travel of the container support.

4. In a labeling machine, in combination, a rotary table, a container support mounted on said table, a label picker disposed adjacent said table and movable into and out of the path of said container support comprising a supporting member, a pair of spaced apart picker finger arms pivotally mounted at their upper ends on said supporting member on axes extending in the direction of the path of travel of said container support, means for urging said picker arms toward one another, adjustable means for limiting the movement of said picker finger arms toward one another, a second set of horizontally disposed pivotal supports for said picker finger arms having their axes extending transversely of the path of said container support, means for limiting the movement of said picker finger arms on said second set of pivots in one direction and means for urging said picker finger arms in the opposite direction.

5. In a labeling machine, in combination, a rotary table, a container clamp mounted thereon and including a vertically movable clamping rod, a label picker disposed adjacent said table and reciprocating laterally along an oscillating shaft, a vertically reciprocating rod for driving said oscillating shaft, a stop on said reciprocating driving rod, a sleeve surrounding said reciprocating driving rod, a coiled spring surrounding said reciprocating driving rod and disposed between said sleeve and said stop, means

for reciprocating said sleeve, a dog on said reciprocating rod below said sleeve and a latch movable in the path of and above said dog by said clamping rod.

5 6. In a labeling machine, in combination, a rotary table, a container support mounted upon said table, a label picker disposed adjacent said table and reciprocally movable transversely of the path of travel into and out of the path of said container support and comprising an oscillating yoke having integrally thereon a pair of downwardly extending spaced apart ears, universally movable pivot means mounted on each of said ears, and picker fingers secured to each of said pivot means, said pivot means permitting the fingers to be separated and swung longitudinally of said path by the engagement of said fingers by a container carried in said support.

7. In a labeling machine, in combination, a 20 rotary table, a container support mounted upon said table, a label picker disposed adjacent said table and reciprocally movable transversely of the path of travel into and out of the path of said container support and comprising an oscillating yoke having spaced apart ears extending downwardly, a first pivot pin extending through each of said ears in the direction of movement of the container support, a second pivot pin rotatably mounted on said first pivot pin transversely thereof; a picker finger secured to each of said second pivot pins, upwardly extending arms rigidly secured to said fingers, a coiled spring interposed between said arms to urge said picker fingers toward one another and spring means connected to said fingers for urging them in a direction opposite to the direction of travel of said container support.

8. In a labeling machine, in combination, a 40 rotary table, a container support mounted upon said table, a label picker disposed adjacent said table and reciprocally movable transversely of the path of travel into and out of the path of said container support and comprising an oscillating yoke having a pair of downwardly extending spaced apart ears, a universally movable pivot means mounted on each of said ears, a picker finger secured to each of said pivot means, spring means connected to said arms for yieldably positioning them, and means for limiting the universal movement of said fingers.

50 9. In a labeling machine, in combination, a rotary table, a container support mounted upon said table, a label picker disposed adjacent said table and reciprocally movable transversely of the path of travel into and out of the path of said container support and comprising an oscillating yoke having a pair of downwardly extending spaced apart ears, a pivot pin mounted in each of said ears and extending in the direction of travel of the container support, a pivot pin carried by each of said first mentioned pivot pins and extending at right angles to said first mentioned pivot pins and a picker arm pivotally mounted on each of said last mentioned pivot pins and yieldable means for positioning said arms in predetermined positions relative to one another and relative to said path of travel.
